UNITED STATES PATENT OFFICE.

LESTER W. KNAPP AND MARTIN W. DORP, OF HOOPESTON, ILLINOIS, ASSIGNEES TO SPRAGUE CANNING MACHINERY COMPANY, OF CHICAGO, ILLINOIS, A CORPORATION OF ILLINOIS.

WASHING AND SCALDING MACHINE.

1,197,831.

Specification of Letters Patent. Patented Sept. 12, 1916.

Application filed July 26, 1915. Serial No. 42,033.

To all whom it may concern:

Be it known that we, LESTER W. KNAPP and MARTIN W. DORP, both citizens of the United States, residing at Hoopeston, in the 5 county of Vermilion and State of Illinois, have jointly invented new and useful Improvements in Washing and Scalding Machines, of which the following is a full, clear, concise, and exact description, reference being had to the accompanying drawings, forming a part of this specification.

Our invention relates to washing and scalding machines, and more specifically to such machines used for washing and scalding materials which are to be used for canning purposes.

One of the objects of our invention is to provide a machine of this character which shall be simple in construction, efficient in 20 operation, and in which improved means are provided whereby the material is subjected to jets of water or steam from jetting coils which are adjustable toward and from the material.

25 Further objects will appear from the detailed description to follow and from the appended claims.

In the drawings, in which we have illustrated one embodiment of our invention— 30 Figure 1 is a side elevation of a washing and scalding machine embodying our invention, showing the supporting frame, the hood and drain pan, and showing in dotted lines the upper and lower jet coils; Fig. 2 is a vertical transverse section near the rear 35 end of the machine showing the manner in which the hood is hinged to the frame and the manner in which the jet coils are secured in place; Fig. 3 is a horizontal sectional 40 view of the rear end of the machine substantially on the line 3—3 of Fig. 2, showing the upper jetting coils, the conveyer which travels beneath these coils, and the clutch mechanism for throwing the conveyer 45 into and out of operation; Fig. 4 is a longitudinal vertical section of the rear end of the machine substantially on the line 4—4 of Fig. 3 showing the construction of the jetting coils and the manner in which they 50 are mounted; Fig. 5 is a rear elevation of a portion of the machine showing the hood raised to permit access to the conveyer and jetting coils; and Fig. 6 is a transverse sec-

tion through one of the pipes of the jetting coil.

Referring now to the drawings in detail our improved machine comprises a supporting frame indicated in general at 10, a conveyer 11, upper jetting coils 12 located above the conveyer, lower jetting coils 13 located beneath the conveyer, rear jetting piping 14 located above the conveyer at the rear of the machine, a hood 15 pivotally mounted on the supporting frame 10 for inclosing the jetting coils and preventing the escape of 60 steam and water, and a drain pan 15^a located beneath the conveyer for collecting and draining off the condensed steam and water which is delivered from the jetting coils.

The frame 10 comprises legs 16 which may be formed from steel channels, longitudinally extending members 17 which may be angle irons, and braces 18 connecting the legs 16 and members 17. The conveyer 11 70 comprises a pair of chains 19, each link of one chain being connected with a link of another chain by means of two rods 20 extending between the chains. The upper runs of the conveyer chains rest on guides or supports 20^a which are secured to the longitudinally extending members 17. Sprockets 21 are provided at each end of the frame over which the conveyer chains 19 pass. The sprockets 21 at the rear end of the machine are secured on a drive shaft 22 which is mounted in bearings 23 secured to the legs 16 of the frame by means of bolts 24. Also secured on the shaft 22 is a drive sprocket 25 provided with a clutch portion 80 26 for engagement with a clutch member 27 which is feathered on the shaft 22. The clutch member 27 has a groove 28 for engagement with the fingers of a clutch operating lever 29 pivotally mounted on the bracket 29^a secured to one of the legs of the frame. The sprockets 21 at the front end of the machine are secured on a shaft 30 which is mounted in bearings 31 secured to the front legs 16 of the frame. The upper jetting coils 12 comprise a header 32 in which are screw-threaded the jetting pipes 33, the other ends of the pipes 33 being closed by means of cap members 34. The jetting coils 12 are supplied with fluid such as water or 90 steam from supply piping indicated in gen-

eral at 36 comprising an elbow 37 communicating with the header, a pipe section 38 screwed into the elbow 37, an elbow 39 in which the pipe section 38 is screwed and a 5 pipe section 40 communicating with the elbow 39. Pipe hangers 41 are secured to the cap members 34 by means of screws 42 extending through openings in the hangers 41 to the cap members. The pipe hangers 41 10 have bent up ears 43 in which are screw threaded the bolts 44 which extend through slots 45 in the arms 46 which are pivotally mounted on the members 17 by means of screws 47.

15 The construction of the arms 46 and supply piping 36 is such that the upper jetting coils can be swung toward and from the conveyer 11 about the screws 47 as pivots. The lower jetting coils 13 are similar to 20 the upper coils 12 but are not adjustable toward and from the conveyer, being supported in fixed pipe hangers 48 secured to the frame of the machine. The rear jet piping 14 comprises a pair of pipe sections 25 49 which are screw threaded into a T-pipe fitting 50 and are closed at their opposite ends by means of pipe caps 51. This piping is mounted on a pair of supports 52 (which are secured to the frame of the machine) 30 by means of screws 53 extending through openings in the supports 52 into threaded engagement with the caps 51. All of the piping of the jetting coils is provided with jet openings 54 shown in detail in Fig. 6. 35 The rear piping 14 is supplied with fluid from a pipe 55 screw threaded into the T-pipe fitting 50. The hood 15 comprises elongated arched sheet metal sections 56 having lateral edged flanges 56^a which are secured to flat reinforcing bars 57. The hood is stiffened by means of reinforcing strips 58 having laterally bent ends 59 secured to the edge flanges 56^a. Provision is made in the hood 15 for the entry of 40 the piping 40, as shown at 60. The drain pan 15^a comprises a trough-like member of sheet material, 61, extending beneath the conveyer and provided with a drain outlet 61^a. The hood 15 is hinged to the supporting frame 10 as shown at 62 (Figs. 2 and 5) and handles 63 are provided to assist in raising the hood. A discharge spout 64 is provided at the rear end of the machine to receive the material from the conveyer. 50

55 The use and operation of our improved machine is as follows: The sprocket 25 is driven from any suitable source of power, not shown. The clutch lever 29 is shifted to move the clutch member 27 into engagement with the clutch portion 26 to start the conveyer to traveling. The material, such as tomatoes, etc., which is to be washed and scalded, is supplied to the conveyer at the front end of the machine in any suitable manner. A portion of the front end of the

conveyer is not covered by the hood so that the material can be inspected if desired to sort out any material which is not to be used. As the material passes into the hood and between the upper jetting coils 12 and the lower jetting coils 13 it is subjected to jets of fluid (which may be steam for scalding the material, or water for washing the material), the jets from the lower piping passing readily up through the conveyer between the rods 20. 70 75

In practice it has been found that two narrow bars 20 for each pair of links of the conveyer chains is the better construction than a single wide bar, as this construction allows the jets from the lower coils to pass through the conveyer into contact with the material carried thereby. A single narrow bar for each pair of links would make the spacing between bars too great for the material which is handled. The upper jetting coils 12 are adjustable toward and from the conveyer in order that they may be adjusted to properly spray the material, no matter what the pressure of the fluid supply. 80 85 This adjustment is also desirable for use with different classes of material and different sizes. The coils may be held in adjusted position in any desired manner, for instance the threaded engagement of the supply piping may be tight enough to hold the coils in any position to which they may be moved. The hood 15 will prevent the escape of steam and will also prevent water or steam from the lower jetting coils 90 from escaping. The condensed steam and water from the jetting coils runs down into the drain pan 15^a and is carried to the drain outlet 61^a. After the tomatoes, or other material, have been scalded by the upper and 95 lower jetting coils they may be subjected to jets of cold water from the rear jetting piping 14 to prevent any further scalding or cooking of the material. The material is delivered from the rear end of the conveyer to the discharge spout 64. 100 105 110

Having thus described our invention what we claim as new and desire to secure by Letters Patent is:—

115 1. In a device of the class described, an elongated frame, a substantially horizontal flexible conveyer supported by said frame and extending longitudinally thereof, jetting means comprising a plurality of jet pipes above the upper run of said conveyer and substantially parallel thereto, means for supporting said pipes for swinging movement toward and from said upper run comprising a plurality of links each having one end pivotally connected to said jetting means, and its other end pivotally connected to said frame adjacent the edge of the upper run of said conveyer, and a hood for housing said jetting and supporting means having one edge pivotally con-

nected to said frame adjacent the edge of the upper run of said conveyer to swing about an axis substantially parallel to said conveyer.

2. In a device of the class described, a conveyer having a substantially horizontal upper run, means for jetting fluid on the material carried by said conveyer comprising a header extending transversely of said

10 conveyer, a plurality of pipes connected with said header, means for supporting said jetting means for swinging movement toward and from said conveyer comprising a member extending transversely of said

15 conveyer for supporting said pipes and forming a closure for the ends thereof, and two swinging links for supporting said transversely extending closure member one pivotally connected adjacent each end of said

20 transversely extending closure member.

3. In a device of the class described, a conveyer, means for jetting fluid on the material carried by said conveyer comprising a jet pipe and a closure for the end of

25 said pipe, and means for supporting said jet means for swinging movement toward and from said conveyer comprising a swinging link pivotally connected to said closure.

4. In a device of the class described, a conveyer, means for jetting fluid on material carried by said conveyer comprising a header and a plurality of pipes communicating therewith, means for supporting said jetting means for swinging movement toward and from said conveyer, and means 35 for supplying fluid to said header comprising a swinging pipe pivotally connected to said header.

5. In a device of the class described, a conveyer, means for jetting fluid on the material carried by said conveyer comprising a header and a plurality of jet pipes connected with said header, and closure means for said pipes, means for supporting said jetting means for swinging movement 45 toward and from said conveyer comprising a swinging link, and means for supplying fluid to said header comprising a swinging pipe pivotally connected to said header, said swinging link being pivotally connected to 50 said closure means.

In witness whereof, we have hereunto subscribed our names.

LESTER W. KNAPP.
MARTIN W. DORP.
